UNITED STATES PATENT OFFICE.

WILLIAM ROY HARMON, OF OAK HILL, FLORIDA.

WHIP-HOLDER.

1,142,703.

Specification of Letters Patent.

Patented June 8, 1915.

Application filed September 29, 1914. Serial No. 864,111.

To all whom it may concern:

Be it known that I, WILLIAM ROY HARMON, a citizen of the United States, residing at Oak Hill, in the county of Volusia 5 and State of Florida, have invented new and useful Improvements in Whip-Holders, of which the following is a specification.

The invention relates to an improvement in whip holders, involving particularly a 10 device of this character, in which the whip may be temporarily locked to prevent accidental displacement, or permanently locked to prevent unauthorized abstraction.

The main object of the present invention 15 is the provision of a whip holder held against casual displacement merely by insertion of the whip in place, providing for locking the parts to make it impossible to release the whip without a proper manipulation of the lock.

The invention in the preferred form of 20 details will be prescribed in the following specification, reference being had particularly to the accompanying drawings, in 25 which:—

Figure 1 is a perspective view illustrating the improvement. Fig. 2 is a central section of the same. Figs. 3, 4, and 5 are sections on line 3—3, 4—4 and 5—5 respectively of Fig. 2.

The improved holder comprises a hollow casing 1, designed to be appropriately secured to any desired part of the vehicle, being arranged so that the whip may be conveniently introduced therewith. Secured within the casing at an appropriate point in its height is a whip holding element 2 including a band 3 secured to the inner wall of the casing, from which band depends 35 spring strips 4 having downward and inward curvature, so as to present a restricted opening below the band for the passage of the whip butt. These springs are preferably, though not necessarily, four in number and when diametrically opposed one pair of greater length than the others, so that the full terminal edge of each spring is free 40 from every other spring, so as to effectively grip the whip butt. Slidably mounted in the band 3 is a releasing member 5 in the form of an elongated sleeve, having a diameter approximating that of the band, so that when the sleeve is depressed, the edge thereof will ride into engagement with the in-

ner surface of the respective springs and 55 force the same apart to release the whip. The releasing member extends through the upper end of the casing 1 and is provided with a head 6 and springs are arranged between the head and top of the casing to normally maintain the releasing member above a position to exert a releasing influence upon the springs 4. The side of the case is provided with a lock 7 in the form of a plug arranged to coöperate with the opening 8 in 60 the releasing member, a key hole 9 being provided adjacent the plug for the reception of the key 10, to permit the plug to be withdrawn to free the releasing member.

With the parts unlocked, it is obvious that 70 upon the introduction of the whip into the holder the butt end will, on passing free ends of the springs 4, be gripped, thereby to prevent casual separation of the whip. Upon downward pressure on the head 6 75 however, the releasing member will spread the springs as described and permit the whip to be freely withdrawn. With the locking plug 7 in position to engage the opening 8 in the releasing member, the latter cannot 80 be depressed, and hence after insertion of the whip, the parts can be operated to release the same only after operation of the key.

What is claimed is:—

1. A whip holder including a casing, a band secured therein, springs depending from the band and projected toward each other to provide a restricted passage, a releasing member including a sleeve operative 90 at one end through the band and adapted for downward movement to engage and spread the springs, the upper end of the sleeve being projected with a head disposed wholly above the upper end of the casing, 95 and springs interposed between the head and casing, whereby on moving the head downward the springs are moved from co-operation with the whip and the whip grasped for removal in a single movement. 100

2. A whip holder including a casing, a band secured therein, springs depending from the band and projected toward each other to provide a restricted passage, a releasing member including a sleeve operative 105 at one end through the band and adapted for downward movement to engage and spread the springs, the upper end of the

sleeve being projected with a head disposed wholly above the upper end of the casing, and springs interposed between the head and casing, said sleeve being formed with 5 an opening and a locking plug operative through the casing to engage the opening to lock the sleeve.

In testimony whereof I affix my signature in presence of two witnesses.

WILLIAM ROY HARMON.
